UNITED STATES PATENT OFFICE

171,001

COMBINED DRINKING CUP, TOOTHBRUSH, AND TOOTHPASTE HOLDER

Robert Mayer, New York, N. Y., assignor to Herman H. Fox, New York, N. Y.

Application July 14, 1953, Serial No. 25,938

Term of patent 7 years

(Cl. D4—3)

To all whom it may concern:

Be it known that I, Robert Mayer, a citizen of the United States of America, and a resident of the city of New York, in the county of New York, and State of New York, have invented a new, original, and ornamental Design for a Combined Drinking Cup, Toothbrush and Toothpaste Holder, of which the following is a specification, reference being had to the accompanying drawing, forming a part thereof:

Fig. 1 is a perspective view of a combined drinking cup, toothbrush and toothpaste holder showing my new design.

Fig. 2 is a vertical cross-sectional view; and

Fig. 3 is an enlarged top plan view thereof.

I claim:

The ornamental design for a combined drinking cup, toothbrush and toothpaste holder, substantially as shown.

ROBERT MAYER.
